ICE CRUSHER

Frank N. Mariani, New York, N. Y.

Application August 26, 1947, Serial No. 770,743

4 Claims. (Cl. 241—84)

1

The subject matter of this invention is a functionally and structurally improved ice crusher wherein a reciprocable plunger effectively cooperates with an appropriate grate to shatter instantaneously and in all directions a block of ice mounted on the grate. The dominant object of the invention is concerned with an ice crusher of the type alluded to particularly adapted for home use and wherein the block of ice is dispersed instantly into relatively small chips on impact by the plunger to preclude packing or clogging of the grate and thus advantageously facilitate dropping of the chips downwardly and through the grate. The invention has as a further object the provision of a serviceable grate or anvil having a plurality of parallel ice block supporting bars each embodying a plurality of primary ice crushing teeth having relatively flat and biased peaks disposed in advance of relatively sharp edges of shaving or ancillary teeth interconnecting the crushing teeth, the arrangement being such that the crushing teeth are disposed along imaginary and concentric circles while the shaving or ancillary teeth which are below the crushing teeth define spaced grooves also located along imaginary and concentric circles. The invention comprehends as a further object the provision of a rugged and durable plunger or hammer having a plurality of concentrically arranged ribs or teeth having flat lower faces adapted to be removably received in the grooves of the grate and defining a plurality of annular concentric channels or grooves for removably receiving the teeth of the bars, the plunger creating on its down stroke an explosive impact against an ice block supported on the blades of the grate whereby the primary teeth of the blades initially but promptly crack and sever the ice block into small fragments while the ancillary teeth shave or reduce the fragments further to permit their falling downwardly through the grate to preclude clogging of the latter by the shattered fragments. Another object is to provide an ice crusher which is easy to load and control and which is quick and reliable in operation. Another object is to provide an ice grate in the form of a cup adapted to be conveniently inserted into and removed from the ice crusher and embodying means to facilitate drainage or comminuted ice particles or chips inadvertently over spilling and including an anti-splash skirt characterizing a nozzle or chute for directing the crushed ice fragments into suitable receptacles as desired. Other salient objects and important advantages will appear from the fol-

2

lowing detailed specification taken with the accompanying drawings wherein:

Fig. 1 is a side elevational view of the ice crusher according to my invention shown in an open relation but partly broken away and partly in section.

Fig. 2 is a transverse sectional view on the line 2—2 of Fig. 1.

Fig. 3 is a sectional view on the line 3—3 of Fig. 2 particularly illustrating the cross head of the reciprocable rack bar.

Fig. 4 is a fragmentary and sectional view on the line 4—4 of Fig. 1 illustrating the reciprocable plunger fully raised from the ice supporting grate or anvil.

Fig. 5 is a view similar to Fig. 4 however showing the plunger on its down stroke and initially contacting the ice block mounted on the grate.

Fig. 6 is a view similar to Fig. 5 but depicting the plunger shattering the ice block in all directions and the chips falling downwardly through the grate.

Fig. 7 shows the plunger at the end of its down stroke.

Fig. 8 is a perspective view of the concentrically ribbed hammer.

Fig. 9 is a plan view of the grate or anvil.

Fig. 10 is a vertical cross sectional view on the line 10—10 of Fig. 9, and

Fig. 11 is a perspective view of the grate shown partly broken away.

According to the invention a grate generally denoted 10 is removably retained by an annular shelf 11 of a fruit juice squeezer of support FJ. Shelf or seat 11 projects from a suitable hollow column 12 having an appropriate base 13 which includes anti-scratching rubber feet 14 and slideable into and out of the column is the guided stabilizer 15 also provided with anti-marring rubber feet 16. Grate 10 serves as an anvil for supporting an ice block 17 adapted to be crushed into small chips on impact of the ribbed or toothed plunger or hammer 18 having its upper end removably and threadably connected to the hollow carrier or hood 19 fastened to the rack bar 20 advantageously reciprocably guided relative to the column.

Fixedly attached to rack bar 20 is the cross head 21 having cam slot 22 cooperating with the eccentrically disposed pin 23 of a crank arm 24 for reciprocating bar 20 on actuation of the rotary handle or lever 26 which includes an extendible and slidably guided manipulatable rod 27.

The handle 26 is suitably rotatably sustained

and effectively drives suitable shaft means 27 having projecting therefrom spaced teeth 28 adapted to cooperate with teeth 29 of bar 20, the arrangement being such that if the crank pin 23 is driving the cross head 21 the speed of the carriage is decelerated. By such an arrangement the carriage on the downward stroke of the handle first moves rapidly then closes slowly and on the opening stroke the carriage first opens slowly and thereafter quickly.

The apparatus hereinbefore referred to apart from the grate 10 and hammer 18 is more fully disclosed in my copending application Serial No. 690,140 filed August 13, 1946, which has become abandoned, for fruit juice extractors and is merely described generally herein for removably sustaining the grate 10 and the ice breaking plunger 18.

In effect the grate 10 is a cup and is in the form of an annular shell 30 having the laterally extending annular rim 31. Integral with shell 30 and arranged therein are the spaced and parallel blades broadly designated 32, 33, 34 and 35. The inside blades 33 and 34 each include spaced primary or crushing teeth 36, 37, 38, 39, 40 and 41 having their apices provided respectively with the flat and downwardly and inwardly sloping or biased faces 42, 43, 44, 45, 46 and 47 (Fig. 10.) Teeth 38 and 39 are at about the same elevation but are disposed below the flat peaks of teeth 37 and 40 which are less in height than the outside and flat peaked teeth 36 and 41. Blades 33 and 34 are desirably beveled to provide ancillary teeth having the cutting or shaving edges 48 integral with, but disposed below and bridging the primary teeth 36 to 41.

The outside blades 32 and 35 each embody four flat peaked primary or crushing teeth 50, 51, 52 and 53 having the flat rectilinear surfaces 54, 55, 56 and 57 sloping downwardly and inwardly. Integral with and interconnecting teeth 50, 51, 52 and 53 are the beveled and shaving teeth arranged between the primary teeth and also providing the intervening cutting or shaving edges 58.

As is evident from an inspection of Fig. 9, primary teeth 38 and 39 of the inner blades 33 and 34 are disposed along an imaginary circle. Primary teeth 51, 52, 40, 40, 52, and 51 of the spaced blades or bars 32, 33, 34 and 35 are also on an imaginary but larger scale. Primary teeth 50, 53, 41, 41, 53 and 50 of the blades are disposed on an even larger imaginary circle. By the arrangement it is apparent that a plurality of annular and concentric rows of primary teeth are formed on the blades of grate 10 desirably spaced apart and consequently constituting a plurality of concentrically arranged grooves in part characterized by the shaving edges 48 and 58 which also form the upper portions of the concentrically arranged ancillary or supplementary shaving teeth disposed at progressively different elevations and below the primary crushing teeth.

Specifically the hammer or plunger 18 embodies the threaded shank 60 removably engaging the internally threaded bore 61 of the carrier or hood 19. The plunger is formed of a suitable hard metal and comprises a solid body having a plurality of annular and concentrically arranged depending and beveled flat bottom or truncated ribs or teeth 62, 63 and 64 radially spaced from the tapered centrally arranged and depending spike or tooth 65. The annular ribs or teeth are disposed at progressively increasing elevations relative to spike 65 and define annular and tapered

channels 66, 67 and 68 which are adapted to receive at least the upper portions of the primary teeth of the blades 32 to 35 when the plunger 18 is in its full down position. The annular ribs 62, 63, and 64 are adapted to be received by the grooves between the primary teeth of the grate which grooves are obviously likewise concentrically arranged and consequently it may be said that the teeth of the blades and the ribs of the plunger or hammer are adapted to removably mesh.

If it be assumed that the ice crusher is in the fully raised or opened position illustrated in Figs. 1 and 4, a block of ice 17 may be readily mounted within the grate or anvil 10 and particularly on the teeth of the blades thereof. Thereafter handle 26 is rotated to cause the crank pin 23 and the pinion defined by teeth 28 to operate rack 20 and it follows the hood is driven downwardly carrying therewith the plunger 18 which applies a crushing downwardly directed force or impact on the ice block shattering the latter instantaneously into small chips and in all directions.

The chips formed fall downwardly through the grate into a tumbler or receptacle (not shown) mounted on the base 13. The lower portion of the shell 30 constitutes a splash precluding nozzle for directing the chips into the tumbler and the annular and truncated insert 70 frictionally fitting on shell 30 and annular rim or flange 31 characterizes means to prevent the chips from falling into flange 31. The insert also aids to drain off residual pieces of ice inadvertently spilling over the shell on the crushing stroke.

As previously stated packing or clogging of the grate is precluded in that if the ice block is insufficiently cracked on the initial part of the crushing stroke of the plunger, the clogging portions of the block remaining on the grate are on the residual portion of the down stroke instantly reduced in size by the cutting edges 48 and 58 of the ancillary or shaving teeth. By such action the grate is kept clear of jamming. Effective shattering of the ice block takes place to prevent clogging even during a single down stroke of the plunger which creates the required explosive and sudden impact against the ice which is cracked and shaped against and by the grate also during a single down stroke of the handle.

Various changes may be made in the details of construction and arrangement of parts without departing from the spirit of the invention or sacrificing any of the advantages thereof inherent therein.

I claim:

1. In an ice crusher, a shell; a grate within said shell and having a plurality of parallel spaced bars disconnected from each other but having their ends only merged with said shell, each of said bars having a plurality of spaced ice cracking teeth and spaced ice shaving teeth integrally interposed between and below said cracking teeth, said cracking teeth of each of said bars having top flattened faces and the top flattened faces of a bar being biased and at progressively higher elevations than the innermost top flattened faces of said last mentioned bar whereby said top faces slope upwardly and outwardly away from the central zone of said grate.

2. In an ice crusher, a shell, a grate within said shell and having a plurality of parallel spaced bars disconnected from each other but having their ends only merged with said shell, each of said bars having a plurality of spaced

ice cracking teeth and spaced ice shaving teeth integrally interposed between and below said cracking teeth, said cracking teeth of each of said bars having top flattened faces and the top flattened faces of a bar being biased and at progressively higher elevations than the innermost top flattened faces of said last mentioned bar whererby said top faces slope upwardly and outwardly away from the central zone of said grate, an annular rim outside of and surrounding said shell intermediate the length thereof and integral therewith, and an upwardly contracted insert mounted on said rim and about said shell.

3. In a device of the character described, a plunger comprising an axially arranged depending spike and having a plurality of concentrically disposed depending and spaced tapered ribs about said spike and arranged upwardly and outwardly relative thereto and in part constituting therewith and with each other a plurality of concentric and spaced channels disposed at progressively higher elevations than the lower part of said spike, said ribs having spaced lower flat substantially horizontal faces at progressively higher elevations than said lower part.

4. In an ice crusher, a shell, a grate within said shell and having a plurality of parallel spaced bars disconnected from each other but having their ends only merged with said shell, each of said bars having a plurality of spaced ice cracking teeth and spaced ice shaving teeth interposed integrally between and below said cracking teeth, said cracking teeth of each of said bars having top flattened faces and the top flattened faces of a bar being biased and at progressively higher elevations than the innermost top flattened faces of said last mentioned bar whereby said top faces slope upwardly and

outwardly away from the central zone of said grate, a plunger removably receivable within said shell for cooperating with said grate and comprising an axially arranged depending spike and having a plurality of concentrically disposed depending and spaced ribs about said spike and arranged upwardly and outwardly relative thereto and in part constituting therewith and with each other a plurality of concentric and spaced channels disposed at progressively higher elevations than the lower part of said spike, said ribs having spaced lower flat substantially horizontal faces at progressively higher elevations than said lower part, and means for displacing said plunger relative to said grate.
